(57) **CLAIM**

The ornamental design of a module for a field termination assembly, as shown and described.

DESCRIPTION

FIG. 1 is a front perspective view of a module for a field termination assembly;

FIG. 2 is a rear perspective view of the module of FIG. 1;

FIG. 3 is a front view of the module of FIG. 1;

FIG. 4 is a left side view of the module of FIG. 1;

FIG. 5 is a right side view of the module of FIG. 1;

FIG. 6 is a rear view of the module of FIG. 1;

FIG. 7 is a top view of the module of FIG. 1;

FIG. 8 is a bottom view of the module of FIG. 1; and,

FIG. 9 is a perspective view of a field termination assembly (such as one used for signal conditioning, energy limiting, galvanic isolation, protection, or a combination thereof) that includes the module of FIG. 1.

The broken lines in the drawings depict portions of module for field termination assembly that form no part the claimed design. The broken lines immediately adjacent to shaded surfaces form a boundary of the claim. The broken lines in FIG. 9 view depict environmental structure and form no part of the claimed design.
